F. X. LOUGHERY, OF KELLEYSVILLE, PENNSYLVANIA.

Letters Patent No. 89,935, dated May 11, 1869

IMPROVEMENT IN WARP-BEAM FOR LOOM FOR WEAVING SKIRTS.

The Schedule referred to in these Letters Patent and making part of the same.

To all whom it may concern:

Be it known that I, F. X. LOUGHERY, of Kelleysville, in the county of Delaware, and State of Pennsylvania, have invented a new and useful Improvement in Looms; and I do hereby declare that the following is a full, clear, and exact description thereof, which will enable others skilled in the art to make and use the same, reference being had to the accompanying drawings, forming part of this specification, in which—

Figure 1 represents a plan view of my improved loom, and

Figure 2 represents a sectional elevation of the same on the line $z z$ of fig. 1.

Similar letters of reference indicate like parts.

The object of this invention is to provide a loom for weaving circular fabrics for skirts and other similar articles.

It consists in the conical yarn-beam, provided with a separating disk, as will be hereinafter more fully described.

A represents the loom-frame; B, the yarn-beam; and C, the cloth-beam.

The-said beams are made larger at one end than at the other, for the purpose of passing the warp through the loom faster on one side than the other, to make circular goods, such as skirt-patterns.

As, under this arrangement, the proportion of weft to the warp would be greater on the short side than on the long side, I propose to compensate for this disproportion by providing a greater amount of warp for the long side, and for this purpose, I provide a reed, having finer spaces on the long side, graduated according to the distance from the end of the reed, on the side where the shortest portion of the fabric is made.

As it is desirable to weave coarser warp-threads into the bottom of the skirt, for a short distance from the side on which the bottoms are woven, I increase the width of the spaces of the reed, and, to prevent the coarser warp-threads from rolling over on to the smaller threads on the warp-beam, I provide a separating disk, D, on the yarn-beam.

Having thus described my invention,

I claim as new, and desire to secure by Letters Patent—

The conical yarn-beam B, provided with the separating disk D, substantially as and for the purpose described.

F. X. LOUGHERY.
